UNITED STATES PATENT OFFICE.

ROBERT J. BROEGE, OF HARVEY, ILLINOIS, ASSIGNOR TO BUDA COMPANY, A CORPORATION OF ILLINOIS.

LUBRICATING DEVICE FOR GAS ENGINES.

1,417,659.

Specification of Letters Patent. Patented May 30, 1922.

Application filed May 10, 1918. Serial No. 233,622.

To all whom it may concern:

Be it known that I, ROBERT J. BROEGE, a citizen of the United States, residing at Harvey, in the county of Cook and State of Illinois, have invented certain new and useful Improvements in Lubricating Devices for Gas Engines, of which the following is a specification.

My invention relates to gas engines, and has reference more particularly to improvements in lubricating systems in engines of this type, these improvements having for their main objects, to increase efficiency in the operation of all moving engine parts; to provide in a lubricating system an efficient force-feed mechanism together with a system of related oil-conducting chambers, passages and ducts whereby said parts are effectively supplied with lubricant, or with an oil mist or fog developed therefrom; to provide a lubricating system wherein the oil is currently utilized in the most economical manner, and in which all dead ends or closed pockets of conduits are eliminated; and to provide a system wherein all parts of the same are accessible for cleaning or overhauling.

These, together with such other objects as may hereinafter appear, or are incident to my invention, I attain by means of a construction illustrated in preferred form in the accompanying drawings, wherein—

Figure 1 represents a vertical sectional view of an engine to which my improved system is shown applied, certain parts of the casing being broken away in different vertical planes in order to disclose interior parts which would otherwise be obscured; Fig. 2 is a cross-sectional view taken transversely of the engine in Fig. 1; Fig. 3 is an enlarged detailed view in cross-section of the well near the end of the cam-shaft; Fig. 4 is a bottom plan view of the same; Fig. 5 represents a similar view to that in Fig. 3, but taken at right-angles thereto, the pump-shaft gears being shown positioned in the well; Fig. 6 is a view detailing the ducts leading to the crank-shaft and cam-shaft bearings; Figs. 7, 8 and 9 represent illustrations of the grooved crank-shaft bearings; and Fig. 10 is a sectional view of the relief valve.

Referring to the drawings, the crank cas-

ing proper comprises the upper half section 11 and the lower half section 12, and is provided with a crank-shaft 13 having a front bearing support 14, a central bearing support 15, and a rear bearing support 16. The numeral 17 designates a cam-shaft having bearings 18 disposed adjacently above the crank-shaft bearings 14, 15, and 16, and supported in circular portions 18' of the casing, the shaft provided at its rear end with a gear 19 disposed in a well 20, formed in the casing, and in which a bath of oil is constantly maintained. The reference numeral 21 indicates the main reservoir which is located between the false bottom 22 and the angular-shaped base 23 of the lower casing section 12, the base being provided at its lowest point with a clean-out plug 24 above which the low and high oil level limits are clearly indicated by the dotted lines in Fig. 1 of the drawings.

Adjacent the rear or left end of the reservoir is a pump casing 25 having within it a pump 27 operatively disposed substantially midway of an oil conducting passage 26 leading angularly from the reservoir to a vertical passage 35 provided in the casing section 12, the inlet end 25a of the passage 26 being protected by the screens 28. In order to keep the screen 28 free from settling or impurities that would otherwise perhaps clog it, the screen is seated in a recess 29 and the base 23 is inclined upwardly to a point above its seating line. The pump 27 consists of a pair of meshed straight tooth gears to which rotary movement is imparted by means of a shaft 30 which is mounted vertically in the casing and at its upper end is provided with a gear 31 adapted to be driven by the cam-shaft gear 19, both of said gears adapted to rotate in the oil contained in the well, the wall of the latter at a point above the rear cam-shaft bearing 18 (Figs. 1, 3 and 5) being formed with an outlet or overflow opening 32. Just below this opening 32 I have provided the upper section of the cam-shaft bearing 18 with a short groove 33, for collecting oil from the cam-shaft surface and leading directly at its end into the well, while the lower sections of all the three cam-shaft bearings are formed with through openings 34, as indicated in Figs. 3 and 6.

Located above the crank-shaft bearing 16

is a portion 36 of the upper casing section 11, and disposed in substantial longitudinal alignment therewith are cast portions 37, 37, located above bearings 14 and 15, a main oil 5 conducting pipe 42 or conduit being mounted in these portions 36, 37, 37, to extend longitudinally of the casing section 11, and through its end walls out of the orbit of the cranks 38, 38. End cleanout plugs 39 are provided for 10 the outwardly extending ends of this pipe.

The central cast portion 37, while not fully shown in Fig. 1, is disclosed in Fig. 6, this showing being also applicable to the front cast portion 37. By referring to Figs. 1, 15 2, 3 and 4, it will be seen that a by-pass or offset recess 40 is formed in the lower portion of member 36 at the terminal of passage 35, by means of which oil is conducted to the main conduit 42 by a pipe 41, and to the 20 rear cam-shaft bearing 18 (through its opening 34) by a pipe 43. In turn, a pipe or passage 44 is provided to conduct oil from main conduit 42 to the rear crank-shaft bearing 16, and it will be noted that pipes 25 43 and 44 do not intersect, the former receiving its supply of oil from by-pass 40 and the latter from conduit 42.

Referring now more particularly to Fig. 6, which illustrates the cast portions 37, 37, 30 of the casing located above the forward and central crank-shaft bearings 14, 15, respectively, and in which the conduit 42 is mounted, I provide in each of these portions a pipe or passage 44' leading similarly as does pipe 35 44 from the conduit 42 to the forward and to the central crank-shaft bearings 14 and 15, and also embody in each of these said portions a pipe or passage 43' leading to the hole 34 in each of the forward and central 40 bearings 18 of the cam-shaft, this pipe intersecting the pipe 44' and receiving its supply of oil from it. It will also be noted that the upper and lower terminals, respectively, of the passages 44' and 43' are provided with 45 clean-out plugs 45 which are screwed into the sides of the castings.

In order that the lubricant may reach the crank-shaft in bearings 14, 15, 16, each of the downwardly inclined pipes 44, 44', 44', 50 55 communicates with an opening 47 formed in the upper bearing section 46 of the crank-shaft. This opening in turn leads to an inner groove 48 in said section and thence into a groove 49 in the lower section, thereby insuring thorough lubrication at these bearings. The bearings for cranks 38 are not grooved but receive a supply of oil from the grooves in the shaft bearings through inclined ducts 50 formed in the crank-shaft, 60 as shown. The upper bearing sections of the cranks, which are associated with the pitmen or connecting rods 51, are provided with openings, similar to the openings 47, which in each case serve to conduct oil to 65 the bearing about each of the connecting rod pins 52 through a pipe 53 disposed lengthwise of the rod 51. Ducts 50 and pipes 53 come into register once during each revolution of the crank-shaft. From the description thus far made, it will be apparent that 70 lubrication of the bearings about the crank-shaft, cam-shaft, cranks, and connecting-rod pins has been efficiently and adequately provided for. And this is equally true in respect to the pump-shaft and its gears. It is 75 also obvious that blind ends of the system have been obviated, permitting the thorough cleaning out of any foreign matter or dirt which may have worked into passages or 80 pipes.

In practice the oil pressure from the pump 27 will perhaps approximate 30 pounds to the square inch per 1,000 R. P. M. of the crank-shaft. Therefore, with a view of preventing hammering and consequent breakage 85 of parts, I provide a relief valve A, such as that illustrated in Fig. 10, wherein the vertical passageway 54 thereof connects with the groove 48 of the forward crank-shaft bearing 14 by means of a slot or opening 55. 90 The upper end of passage 54 is closed by the plug 56, below which the passage is enlarged to receive and form a seat for the valve ball 57, the ball being normally held on its seat 58, below the side apertures or outlets 59, 95 60, by the spring 61. This relief valve is located just behind the portion 37 shown at the right of Fig. 1. Should the pump force a surplusage of oil toward the bearings, the excess pressure in the system operates to lift the ball 57 permitting a flow of oil through the lower relief aperture 59. 100 In the event that the pressure should tend to press the ball sidewise into this aperture, then oil will flow past the ball and thence outwardly through the upper aperture 60. 105 These apertures are formed in the forward transverse partition 62 of the casing section 11, and above the level of the cam-shaft bearings 18. The oil discharging from apertures 59 and 60 spills downwardly past the front crank-shaft bearing 14 into a pocket or well 63 formed in the forward end of the lower section 12 of the casing, and overflows from that pocket over a dam 64 on to the 110 false bottom 22 and thence flows into the reservoir 21 through the opening 65 formed centrally in said false bottom. The dam 64 is constructed sufficiently high enough to maintain the teeth of the timing gear 66 in a constant bath of oil.

During the running of the engine the 115 whole interior of the casing is filled with a fine vapor of oil of about the consistency of fog. The rapid action of the moving parts 120 with respect to the lubricant and lubricant overflow, causes this fog to form, and circulate and permeate into every nook and cranny of the casing, and, furthermore, in 125 addition to lubricating all of the valve cams 130

67 and tappets 68, this fog passes upwardly through holes 69 formed in the cylinder casting covering casing section 11 to lubricate the valve springs 70 and stems 71.

5 With the engine in operation, rotation is imparted to the force feed pump 27 through the media of shaft 30 and gears 19 and 31, which induces a flow of lubricant from the reservoir through passages 26, 35, to the by-pass 40 and thence upwardly to main conduit 42 and to the rear cam-shaft bearing 18. The groove 33 formed in this bearing catches oil during cam-shaft rotation and in feeding into well 20 tends to keep the well replenished. Any overflow naturally passes out of the well through outlet 32 and spills on to the moving cam and crank shafts, and that portion of the overflow which has not been transformed into oil mist passes through opening 65 into the reservoir for further circulation. As already described, the crank-shaft bearings are lubricated by the main-conduit branch-pipes 44 and 44'; the front and central cam-shaft bearings by pipes 43' which branch from the pipes 44'; the bearings about the cranks 38 by ducts 50; gears 19 and 31 by the oil bath in well 20; timing gears by the oil in well 63; the connecting pin bearings by passages 53; and all valve parts by the oil splash or fog generated during the active operation of the engine parts. The oil pump, it will be noted, is submerged and its suction end so arranged as to have the intake on a level with the low oil level which is above the settling sump. All surplus oil is eventually deposited or discharged on to the false bottom and thence flows into the reservoir for re-circulation through the system.

40 What I claim is:

1. In combination, an engine casing having a bearing and an oil conducting passage leading to said bearing, a relief valve for said passage, and a gear lubricating walled pocket formed in the casing below the bearing and adapted to receive the overflow from said relief valve.

2. In combination, an engine casing having a bearing, an oil conducting passage leading thereto, a relief valve for said passage mounted in said bearing, a gear disposed adjacent said bearing, and an oil well for said gear adapted to receive the overflow from said relief valve.

55 3. In combination, an engine casing having a reservoir and formed with an oil containing walled pocket, a pumping device for said reservoir and means for actuating said device including gearing disposed in said pocket and adapted to rotate in the oil contained therein, the wall of said pocket provided with an outlet above said gearing and located so that overflow therethrough may gravitate toward said reservoir.

60 4. In combination, an engine casing formed

with a bearing and an oil containing walled pocket, at one side of said bearing, oil-pump actuating gearing journaled in said bearing and disposed in said pocket to rotate in the oil contained therein, an oil conducting passage leading upwardly to said bearing and an oil collecting passage or groove adapted to register with said passage and deliver oil to said pocket during gear rotation.

5 In combination, an engine casing formed with an oil containing walled pocket, oil-pump actuating gearing disposed in said pocket to rotate in the oil contained therein, and an oil collecting passage or groove adapted to deliver oil to said pocket during gear rotation, the wall of said pocket provided with an outlet located above said gearing and said groove.

6 In a device of the character described, the combination with an engine casing and its crank and cam-shafts, said shafts offset vertically and horizontally in respect to one another, of a main oil conduit intermediate said shafts, intersecting passages constructed and arranged to receive their supply of oil from said conduit at the point of intersection and conduct the same to said shafts, a pocket in the casing extending downwardly below the point of intersection of the said passages, and plug cleanout means for said pocket.

7 The combination with an engine casing and its crank and cam-shafts, and bearings therefor, of a force feed lubricating device for conducting oil under pressure to the bearings of said shafts, and a relief valve therefor positioned in said casing at a point above the maximum swing of the crank-shaft bearings and the lowest arcs of the cam-shaft bearings.

8. The combination with an engine casing having an upper cam-shaft bearing and a lower crank-shaft bearing, of an oil reservoir in said casing, a portion of said casing formed with a by-pass, oil impelling means including an upwardly directed oil conduit leading from the reservoir to said by-pass, an oil conduit substantially horizontally disposed in the casing above the by-pass and having a duct communicating with the crank-shaft bearing, and a pair of ducts independently leading from the by-pass to the horizontal conduit and to the cam-shaft bearing.

9. In a gas engine, the combination with an engine casing and its crank and cam-shafts, and bearings therefor, of a main oil conduit adjacent one of said shafts, a force feed lubricating device for conducting oil under pressure to said conduit, and intersecting passages constructed and arranged to receive their supply of oil from said conduit at the point of intersection and being capable of conducting the same to said bearings.

10. In a gas engine, the combination with an engine casing and its crank and cam shafts, and bearings therefor, of a main oil conduit adjacent one of said shafts, a force feed lubricating device for conducting oil under pressure to said conduit, intersecting passages constructed and arranged to receive their supply of oil from said conduit at the point of intersection and being capable of conducting the same to said bearings, said 10 passages extending through a cast portion of the casing, and removable plug means in said casing portion for said passages.

ROBERT J. BROEGE.
